UNITED STATES PATENT OFFICE.

CLAUDE C. GOULD, OF BATAVIA, ASSIGNOR TO THE EASTERN ELECTRICAL MANUFACTURING COMPANY, OF WHEATFIELD, NEW YORK.

TELEPHONE SWITCH-BOARD.

SPECIFICATION forming part of Letters Patent No. 392,326, dated November 6, 1888.

Application filed December 22, 1887. Serial No. 258,638. (No model.)

To all whom it may concern:

Be it known that I, CLAUDE C. GOULD, of Batavia, in the county of Genesee and State of New York, have invented new and useful Improvements in Telephone Switch - Boards, of which the following is a specification.

This invention relates to an improvement in that class of telephone switch-board systems in which each subscriber's line is provided at 10 to the central office with a movable terminal which is automatically moved out of its normal position so as to break the ground-connection upon sending a current through the line. Switch-board systems of this kind are described and shown in Letters Patent of the 15 United States Nos. 355,928 and 355,929, granted to C. C. Gould and W. Smith, dated January 11, 1887.

The object of my invention is to provide a 20 simple switch system of this character, in which the movements required in the operation of connecting subscribers are reduced to a minimum.

My invention consists to these ends of the 25 improvements, which will be hereinafter fully described, and pointed out in the claims.

In the accompanying drawings, consisting 30 of two sheets, Figure 1 is a fragmentary cross-sectional elevation of a switch-board provided with my improvement. Fig. 2 is a horizontal section in line *x* *x*, Fig. 1. Fig. 3 is a horizontal section in line *y* *y*, Fig. 1. Fig. 4 is a cross-section of one of the plugs on an enlarged scale. Fig. 5 is a front elevation of two switch-boards arranged side by side, showing the manner 35 of connecting subscribers on different boards. Fig. 6 is a modified construction of the plug.

Like letters of reference refer to like parts 40 in the several figures.

A represents the upright portion and *A'* the horizontal or table portion of the switch-board. The table portion *A'* is provided with depressions or cavities, in which the subscribers' plugs *B* are held in a vertical position by weights *B'* and cords *b*.

C represents the annunciator, which is supported upon a shelf, *c*, extending backwardly from the rear side of the upright portion *A*.

C' represents the annunciator-frame, which

consists of a base, *c'*, and two standards, *c²* *c³*, formed with or secured to the base *c'*.

c⁴ *c⁵* represent the coils secured horizontally to the front standard, *c²*.

d represents the vibrating armature pivoted 55 at *d'* to the upper end of the rear standard, *c³*, and provided with a horizontal arm or lever, *d²*, projecting forwardly beyond the upright portion *A*.

E represents the apron or drop of the annunciator arranged on the front side of the portion *A*. The apron *E* is pivoted at its lower end to a horizontal plate, *e*, formed on the front standard, *c²*, and projecting forwardly through an opening formed in the upright portion *A*. The apron *E* is held in an elevated position by a nose or hook, *d³*, formed on the outer end of the horizontal lever *d²* of the armature *d*.

e' represents a horizontal lip formed near 70 the lower end of the apron *E*, on the rear side thereof, and which is adapted to strike against the upper side of the horizontal plate *e* and limit the backward movement of the apron. The lip *e'* is preferably cast integral with the 75 apron *E* and made of such a thickness as to permit the same to be easily bent to properly adjust the backward movement of the apron.

e² represents a light tension-spring secured 80 at one end to the lever *d²* of the armature *d* and at its opposite end to an adjusting-screw, *e³*, secured to the front standard, *c²*, of the annunciator-frame. The screw *e³* projects forwardly through an opening in the upright portion *A*, and is arranged in line with and in rear of an 85 opening, *e⁴*, formed in the apron *E*. The opening *e⁴* permits of the introduction of a screw-driver when it is desired to turn the screw *e³* to regulate the tension of the spring *e²*.

F represents a metallic switch-lever pivoted 90 at its rear end to a standard, *F'*, secured to the upper side of the shelf *c*.

f represents an upwardly and downwardly curved arm formed on the front end of the lever *F* and terminating in a hook, *f'*. The latter engages against the lower side of a cross-bar, *f²*, of a non-conducting link, *f³*, secured to the inner end of a horizontally-movable locking-bolt, *g*. The locking-bolt *g* is guided in openings formed in the annunciator-frame *C'* 100

and projects with its outer end through an opening formed in the upright portion A of the switch-board.

h represents a tongue or tail-piece formed on the apron E below its pivot, and which is adapted to strike against the bolt g and move the latter backwardly out of engagement with the hook f' of the switch-lever F when the apron E is released. The backward movement of the locking-bolt g is limited by a pin, g', which strikes the standard c². The locking-bolt g is held in a forward position by a spring, g², interposed between a pin, g', and the standard c³ of the annunciator-frame C'. The locking-bolt g is held from turning by a flat rearwardly-projecting ear, g⁴, formed on the rear standard, c³, of the annunciator-frame adjacent to the lower flat side of the link f².

H represents a spiral spring secured at one end to the switch-lever F and at its opposite end to a metallic angle-plate, i, attached to the shelf c. The spring H is secured to the plate i by means of an adjusting-screw, i', whereby the tension of the spring can be regulated. The spring H causes the switch-lever F to swing upwardly on its pivot when released from the locking-bolt g.

I represents the main line connected with the subscriber's instrument J and with the annunciator C, as clearly shown in Figs. 1 and 2.

K K' represent two flat contact-springs secured to the under side of the shelf c on opposite sides of an arm or finger, k, formed on the switch-lever F below the curved arm f. The arm k projects downwardly through an opening, k', formed in the shelf c. The contact-spring K is connected with the annunciator C by the main line I, and the contact-spring K' is connected with the ground by a wire, l.

l' represents a transverse metallic pin secured to the arm k of the switch-lever F by a non-conducting ring or bushing, l².

As shown in Fig. 2, the contact-springs K K' are connected by means of the metallic pin l' when the switch-lever is locked by the bolt g. Upon releasing the switch-lever from the locking-bolt g the arm k of the switch-lever is raised from contact with the springs K K', and the ground-connection is broken.

L represents a wire connecting the contact-spring K with the cord b of the plug B.

m represents the handle or non-conducting portion of the plug B, and m' the metallic stem of the same secured to the handle m by a screw-threaded shank, m².

m³ represents a longitudinal opening formed in the handle m, through which the cord b is introduced. The latter passes upwardly through the opening m³ of the handle m, and is wound or curled at m⁴ around the shank m², and is securely held in place by a metallic contact-cap, m⁵, which fits snugly over the upper end of the plug B, and is held thereon by a shoulder, m⁶, formed on the stem m'. The shoulder m⁶ of the stem m' causes the cap m⁵ to compress the curled portion m⁴ of the cord b and firmly secure the same in the handle, so

as to form a reliable contact between the parts. If desired, the shoulder m⁶ of the stem m' of the plug may be dispensed with, and the cap 70 m⁵ be provided with an internal screw-thread, and the plug B with an external screw-thread, as clearly shown in Fig. 6.

N represents an arm formed on the rear end of the switch-lever F, and projecting downwardly through an elongated opening, n, formed in the shelf c, and bearing with its lower curved end against a flat metallic contact-spring, N', secured to the under side of the shelf c.

n' represents a wire connecting the contact N' with the main line I.

N² represents the local outsocket, constructed of non-conducting material and moving in a sleeve, n², secured to the upright portion A. 85 The socket N² is made tubular and slightly flaring at its outer end, to facilitate the introduction of the plug B into the same.

n³ represents a metallic contact-spring secured to the rear end of the socket N² by an 90 ear, n⁴, and a screw-threaded shank, n⁵, and arranged with its curved front end in the opening of the socket N².

n⁶ represents a wire, which connects the contact-spring n³ of the outsocket N² with the 95 main line I. Each section or switch board is provided with as many local outsockets N² as there are subscribers arranged on said board.

N³ represents a non conductive bar secured at one end to the ear n⁴ of the socket N², and 100 pivoted at its opposite end to the lower end of the arm N of the switch-lever F. The bar N³ causes the socket N² to move outwardly to the position shown in dotted lines in Fig. 1, when the switch-lever F is released from the locking-bolt, and this movement of the socket notifies the operator that a subscriber has called.

O O' represent two pedals arranged side by side and pivoted in standards o, secured to a cross-bar, o', and held in an elevated position 110 by suitable springs, o².

P represents the operator's listening-telephone connected by wires p p' with contact-springs p² p³, respectively. The contact-springs p² p³ are secured to the cross-bar o' underneath 115 and in line with two similar contact-springs, p⁴ p⁵, secured to the under side of the pedal O.

Q represents the generator connected by wires q q' with contact-springs q² q³, respectively. The contact-springs q² q³ are secured 120 to the cross-bar o' underneath and in line with two similar contact-springs, q⁴ q⁵, secured to the under side of the pedal O'.

q⁶ represents a wire connecting the contact-point p⁴ of the pedal O with the ground, and 125 q⁷ represents a wire connecting the contact q' of the pedal O' with the ground.

R R' represent thimbles or finger-tips constructed, preferably, of pliable non-conductive material, and which are adapted to be applied 130 to the index-finger of both hands of the operator.

r represents metallic contact-surfaces secured in any suitable manner to the thimbles

R R', and which are adapted to be pressed against the metallic caps m^5 of the plugs B. The contact-surfaces r are connected by a conducting-cord, r' , which passes over the shoulders of the operator.

r^2 represents a wire or cord extending, preferably, upward from the central rear portion of the shoulder-cord r' to a suitable point above the switch-board, as shown in Fig. 5, and which is connected at its lower end by a wire, r^3 , with the contact-point p^5 of the pedal O, and with the contact-point q^5 of the pedal O' by a wire, r^4 .

R^2 represents non-conductive thimbles secured to the thumbs of the operator to lessen the liability of shocks. If desired, however, the metallic contact-surfaces r may be secured to the index-fingers of gloves to be worn by the operator; but I prefer the construction shown as it is less cumbersome. If desired, the thimbles may be dispensed with on one or the other hand, as the operator may desire; but by having them on both hands the operator is enabled to use the thimble on the hand located nearest to the plug to be used, whereby the operation of connecting the subscribers is greatly facilitated.

In Fig. 1 of the drawings the pedal O is shown in a depressed position, showing the hand contact-points r connected with the operator's listening-telephone P; but the contact-springs of both pedals O O' are held out of engagement with the contact-springs $p^2 p^3$ and $q^2 q^3$ of the cross-bar o' by the springs o^2 when the pedals are in their normal position.

S represents outsockets secured in the upright portion A, below the sockets N^2 .

Each switch board or section is provided with as many outsockets S as there are subscribers' terminals arranged on the other sections or tables in the same exchange. Each outsocket S is provided with a contact-spring, s , which is connected with the switch-lever F of the subscriber, which it represents by a wire, s' , an angle-plate, i , and a spring, H, as clearly shown in Fig. 5, and these sockets are numbered to correspond with that of the switch-lever F with which they are connected.

T represents a contact-spring arranged underneath the shelf c in front of the arm N of the switch-lever F, and t represents a V-shaped contact-surface formed on the arm N of the switch-lever F, and which is adapted to engage against the spring T and form a contact therewith when the switch-lever F is released from the locking-bolt g .

t represents a wire which connects the contact-point T with the main line I.

U, Fig. 3, represents the night-bell connected by a wire, u , with a switch-lever, u' , of a switch, U', and by a wire, u^2 , with the battery u^3 .

$u^4 u^5$ represent spring-contacts arranged opposite and below a short rearwardly-projecting arm, u^6 , formed on the lever F, and which are secured to the top of the shelf c .

u^7 represents a laterally-projecting contact-

pin secured to the arm u^8 of the switch-lever F, and adapted to connect the contact-springs $u^4 u^5$ of the night-bell circuit when the switch-lever F is released from the locking-bolt g .

u^8 represents a wire connecting the contact-spring u^5 with the battery u^3 , and u^9 represents a wire connecting the contact-spring u^4 with a dead contact-point, u^{10} , of the switch U'.

Figs. 1 and 2 represent the parts of the switch in their normal position, and the subscriber's main line I is connected with the ground at the central office by the contact-spring K, lateral pin l' , contact-spring K', and wire l .

In making a connection between two subscribers arranged upon the same board or section the operation is as follows: When the subscriber calls the central office, the vibration of the armature d releases the apron E, which causes the tongue h of the apron to strike against the free outer end of the locking-bolt g and move the latter backwardly out of engagement with the hook f' of the switch-lever F. The latter is now swung upwardly by the spring H which disconnects the contact-springs K K' and breaks or opens the line. This upward movement of the switch-lever causes the lower curved end of the arm h of the switch-lever to strike against the end of the link f^3 and move the locking-bolt g forwardly, so as to cause the latter to strike against the tongue h of the apron E and return the same to its elevated position in engagement with the hook d' of the armature d .

The line being open, the calling subscriber can no longer ring his bell, and from this fact he knows that his call has been received at the central office. The subscriber's call is made known to the operator by the calling subscriber's outsocket N^2 moving forward to the position shown in dotted lines in Fig. 1. The operator now depresses the pedal O to the position shown in Fig. 1, and at the same time grasps the calling subscriber's plug B, so as to form a contact with the metallic cap m^5 thereof by the hand-contact r . The operator's listening-telephone is now connected with the calling subscriber's line I by the contact-spring K, wire L, cord b, metallic contact-cap m^5 of the plug B, hand-contact r , shoulder-cord r' , wire r^2 , branch wire r^3 , pedal contact-spring p^5 , stationary contact-spring p^3 , wire p' , listening-telephone P, return-wire p , stationary contact-spring p^2 , pedal contact-spring p^4 , and wire q^6 to the ground.

When the operator has ascertained with whom the calling subscriber desires to be connected, she releases the pedal O, so as to break the connection with the listening-telephone, and retains her grip on the cap m^5 of the plug B of the calling subscriber, and inserts the shank m' of the same into the outsocket N^2 of the called subscriber sufficiently to form a contact with the spring n^3 thereof, thereby connecting both subscribers. At the same time that she performs this last-mentioned operation she de-

presses the opposite pedal, O', and thereby

connects the generator with the main lines of both subscribers, ringing them simultaneously. The generator Q is connected in this manner with the main line by the calling subscriber's contact-spring K, wire L, cord b, plug B, as above described, hand-contact r, shoulder-cord r', wire r², branch wire r⁴, pedal contact-spring q⁵, contact-spring q³, wire q⁴, generator Q, return-wire q, contact-spring q², to pedal contact-spring q¹, and wire q¹ to the ground. By thus placing the calling subscriber's plug B into the outsocket N² of the called subscriber and connecting the generator the called subscriber's armature is caused to vibrate, and releases the apron E and switch-lever F of the called subscriber. The upward movement of this switch-lever F again replaces the called subscriber's apron E in the same manner as in the case of the calling subscriber's first call, and the continued vibration of the calling subscriber's armature causes his apron E to again fall and remain in this fallen position.

By releasing the switch-lever F of the called subscriber, as above described, his outsocket N² is moved forwardly to the position shown in dotted lines in Fig. 1. The operator now fully inserts the shank m' of the calling subscriber's plug into the socket N² of the called subscriber, the plug being held from moving backward sufficient to again replace the ground-connection by an inclined nose or hook, s², formed on the lower side of the outsocket N², and which strikes against a shoulder or projection, s³, formed on the sleeve n². The operator now releases the plug B and allows the pedal O' to return to its elevated position, thereby breaking the connection with the generator. The operator now imparts a rapid backward movement to the calling subscriber's outsocket N², which causes the lower curved end of the arm k of the switch-lever F to be moved downwardly sufficient to strike against the rear end of the locking-bolt g, and thereby cause the latter to move forward so as to replace the fallen apron to its elevated position in engagement with the hook d³ of the armature, ready to be rung off. The switch-lever F and outsocket N² are again returned to their abnormal position by the spring H as soon as the operator releases the socket N². The calling and called subscribers' instruments are now connected by the calling subscriber's main line I passing to and through his annunciator C to the contact-spring K, wire L, plug B, called subscriber's outsocket N², wire n², and called subscriber's main line I.

When the subscribers ring off the calling subscriber's armature d is again vibrated, the apron drops, and remains in this position, thus notifying the operator that the subscribers have finished. The operator now removes the plug B from the outsocket N² of the called subscriber and replaces the switch-levers F of both subscribers and the apron E of the called subscriber by simply raising the outsockets N² sufficiently to allow the depending inclined

hooks s² of the outsockets N² to clear the shoulders s³ of the sleeves n², and then forcing the sockets backwardly until the switch-levers F are again securely locked in engagement with their respective locking-bolts g, ready for another call.

It is obvious that the operator can first fully insert the calling subscriber's plug B into the outsocket N² of the called subscriber before depressing the pedal O' and connecting the generator Q with the hand contact-surfaces r.

If a subscriber is wanted whose terminal is located on some other section or table, the operator inserts the plug B of the calling line into the outsocket S of the called line and retains her grip on the plug B, as above described. The calling subscriber is now connected with the called subscriber's actuating mechanism from the calling subscriber's main line I, to and through his annunciator C, to the contact-spring K, wire L, calling subscriber's plug B, called subscriber's outsocket S, wire s', angle-plate i, actuating-spring H, switch-lever F and arm N thereof, contact-spring N', wire n', to called subscriber's main line I, to and through his annunciator C, by the contact-springs K K' and lateral contact-pin l', to the ground by the wire l. The operator now depresses the pedal O' and connects the generator Q with both lines by applying the hand contact r to the plug B. This last movement causes the aprons E of both subscribers to fall and remain in this fallen position by the continued vibrations of the armature d. This fallen position of the apron E of the called subscriber notifies the operator at the section or table on which the called subscriber's terminal is located that this subscriber is being handled by an operator on some other section or table. By thus applying the generator the connection between the subscribers is completed by the lever F of the called subscriber being released from the locking-bolt g and breaking this subscriber's ground at the central office. The upward movement of the switch-lever F and the forward movement of the arm N thereof breaks the connection between the latter and the contact-spring N' and connects the arm N with the contact-spring T, wire t', and main line I. The subscribers are now connected by the calling subscriber's main line I to and through his annunciator to the plug B, as above described, called subscriber's outsocket S, wire s', angle-plate i, actuating-spring H, switch-lever F and arm N thereof, contact-spring T, wire t', main line I, to and through annunciator C, to the called subscriber's instrument. The operators now replace the fallen aprons E of both subscribers by imparting a rapid backward movement to the sockets N², as above described.

When two or more subscribers are located upon the same line and one of said subscribers calls the central office, causing the apron to fall and release the switch-lever, as above described, and the operator ascertains that said subscriber desires to be connected with an-

other subscriber arranged upon the same line, she again replaces the ground by moving the outsocket N^2 of this line backwardly to its normal position, as above described. The 5 operator now locks the switch-lever F and out-sockets N^2 by turning a hook, n^7 , arranged above the socket, to a vertical position, as shown in dotted lines in Fig. 1. The calling subscriber can now call the subscriber wanted 10 by ringing his bell the required number of times in the usual manner. The operator now raises the fallen apron ready to be rung off. When the subscribers have rung off, the operator releases the socket N^2 by turning the hook 15 n^7 back to its horizontal position and again replaces the socket N^2 to its normal position ready for another call.

I claim as my invention—

1. The combination, with the main line and 20 a plug connected therewith, of a hand-contact adapted to be applied to said plug, a generator, a stationary contact-point connected with said generator, and a movable contact-point connected with the hand-contact and adapted 25 to engage with the stationary contact-point, whereby the generator is connected with the hand-contact, substantially as set forth.

2. The combination, with the main line and 30 a plug connected therewith, of a hand-contact adapted to be applied to said plug, an operator's listening-telephone, a stationary contact-point connected with said listening-telephone, and a movable contact-point connected with 35 said hand-contact and adapted to engage with the stationary contact-point, whereby the listening-telephone is connected with the hand-contact, substantially as set forth.

3. The combination, with the main line and 40 the plug connected therewith, of a hand-contact adapted to be applied to said plug, a generator, an operator's listening-telephone, stationary contact-points connected with the generator and with the operator's listening-telephone, and movable contact-points connected 45 with the hand-contact and adapted to engage with said stationary contact-points, whereby the generator and the listening-telephone are connected with said hand-contact, substantially as set forth.

50 4. The combination, with the main line and the plug B, of the thimble R, provided with a hand-contact, r , a cord, r' , connected with the hand-contact, and a wire, r'' , leading to the switch, whereby said hand-contact is connected 55 with the generator and the operator's listening-telephone, substantially as set forth.

5. The combination, with the main line and 60 the plug connected therewith, of a thimble, R, provided with a contact, r , a cord, r' , connected with said hand-contact, contacts $q^2 q^3$, connected with the generator, a pedal, O', provided with movable contacts $q^4 q^5$, adapted to engage against the contacts $q^2 q^3$ when in a depressed position, a wire, q^6 , connecting the 65 movable contact q^4 with the ground, and a wire, r^3 , whereby the movable contact q^5 is

connected with the hand-contact, substantially as set forth.

6. The combination, with hand-contact r , listening-telephone P, and the generator Q, of 70 stationary contacts $p^2 p^3$ and $q^2 q^3$, connected, respectively, with the listening-telephone and with the generator, pedal O, having contacts $p^4 p^5$, adapted to connect with the hand-contact r and with the contacts $p^2 p^3$ of the listening-telephone, and a pedal, O', having contacts $q^4 q^5$, adapted to connect the hand-contact r with the contacts $q^2 q^3$ of the generator, 75 substantially as set forth.

7. The combination, with the stationary contacts $p^2 p^3$ and $q^2 q^3$, of the pedal O, having contacts $p^4 p^5$, adapted to connect, respectively, with the contacts $p^2 p^3$, a pedal, O', having contacts $q^4 q^5$, adapted to connect, respectively, with the contacts $q^2 q^3$ and springs o^6 , whereby 85 the pedals O O' are held in an elevated position out of engagement with the stationary contact-points, substantially as set forth.

8. The combination, with the main line and 90 a contact, K, connected therewith, of a pivoted switch-lever, a contact secured to said switch-lever and connecting the contact K with the ground, a locking-bolt, g , whereby the switch-lever is held in a depressed position, an 95 apron connected with the armature of said annunciator and having a depending lip adapted to strike against the locking-bolt g when said apron is released, and thereby release the switch-lever F from the locking-bolt and breaking 100 the ground-connection of the main line, substantially as set forth.

9. The combination, with the main line and 105 a pivoted switch-lever having a contact connecting the main line with the ground, a locking-bolt, whereby said switch-lever is held in its normal position, an apron, E, adapted to release said locking-bolt and the switch-lever, an arm, h , whereby said apron is returned to 110 its elevated position, and an actuating-spring, whereby the switch-lever is held in its abnormal position, substantially as set forth.

10. The combination, with the annunciator mechanism and the locking-bolt, of a switch-lever connected with the locking-bolt, and a 115 contact-socket which is connected with said switch-lever and moved out of its normal position when said switch-lever is released, substantially as set forth.

11. In a switch-board system, the combination, with the main line I and the annunciator mechanism, of an outsocket, S, a switch-lever, F, a wire, s' , whereby the socket S is connected with the switch-lever F, and contact N' , connecting said switch-lever with the main line 120 I, substantially as set forth.

12. In a switch-board system, the combination, with the main line I and the annunciator mechanism, of an outsocket, S, a switch-lever, F, a wire, s' , whereby the socket S is 125 connected with the switch-lever F, a contact, N' , connecting said switch-lever with the main 130

line when the lever is in its normal position, and a contact, T, whereby the switch-lever is connected with the main line when in an abnormal position, substantially as set forth.

5 13. In a switch-board system, the combination, with the main line and the switch-lever F, of a night-bell, U, contacts u^4 u^5 , connected with said night-bell, and contact-pin u^6 , of the switch-lever F, whereby the contacts u^4 u^5 are

connected when said switch-lever is in an abnormal position, substantially as set forth.

Witness my hand this 23d day of November, 1887.
